[57] CLAIM

The ornamental design for a rotary mixer for pharmaceutical vials, as shown and described.

DESCRIPTION

FIG. 1 is a right front perspective of a rotary mixer for pharmaceutical vials, showing our new design;

FIG. 2 is a top plan view;

FIG. 3 is an elevational view of one side, the other side elevational view being substantially a mirror image thereof;

FIG. 4 is a rear elevational view;

FIG. 5 is a bottom plan view;

FIG. 6 is a front elevational view; and,

FIG. 7 is a side elevational view with the top cover, having top and front transparent viewing panels, being raised into a position for loading or unloading the vials.
